SCISSORS

Byron L. Atchison, Abilene, Kans.

Original application September 16, 1937, Serial No. 164,260. Divided and this application January 18, 1940, Serial No. 314,547

7 Claims. (Cl. 30—254)

This invention relates to an improved construction of scissors and constitutes a division of my former copending application, filed September 16, 1937, Serial No. 164,260.

5 It is a primary aim of this invention to provide an improved construction of scissors comprising the combination of a novel construction of shear frame, a detachable holder for detachably connecting a razor blade to one of the jaws 10 of the frame, and a second holder having an integral blade element for co-acting with the razor blade to provide the cutting blades of the scissors.

A particular advantage of the invention resides 15 in the fact that the blade holder may be readily detached from the razor blade to provide for ready replacing of the razor blade while the holder provided with the integral blade element may likewise be readily detached for sharpening 20 or replacing.

Another object of the invention is to provide a 25 novel form of blade holder and supporting jaw to enable the blade holder to be readily detached and reversed so that the razor blade, carried thereby, may be employed as a knife.

Other objects and advantages of the invention 30 will hereinafter become more fully apparent from the following description of the drawing, which illustrates a preferred embodiment thereof, and 35 wherein—

Figure 1 is a side elevational view showing the 30 scissors assembled and in a closed position.

Figure 2 is a similar view showing the razor 35 blade holder reversed to position the razor blade for use as a knife.

Figure 3 is a transverse sectional view taken substantially along the plane of the line 3—3 of Figure 1, and

Figures 4 and 5 are perspective views of the 40 razor blade holder and the cutter frame, respectively.

Referring more particularly to the drawing, wherein like reference characters designate like or corresponding parts throughout the different 45 views, 10 designates generally the shear frame comprising a pair of jaws, designated generally 11 and 12 which are provided with integrally formed handles 13 and 14, respectively. The jaws 11 and 12 are pivotally connected at 15 adjacent the shank ends of the handles 13 and 14. Jaws 11 and 12 each include the integral portions 16 and 17 which are disposed substantially at 50 right angles to each other. The portions 17 are formed integral with the shank ends of the handles 13 and 14 at the pivot 15 and are disposed

in aligned oppositely projecting relationship when the jaws 11 and 12 are in a closed position so that the portions 16 are disposed in spaced apart, substantially parallel relationship.

The portions 16, as best seen in Figure 3, are 5 polygonal shaped in cross section. A razor blade holder, designated generally 18, includes a head portion 19 which is recessed to receive the portion 16 of either of the jaws 11 or 12. As illustrated, the holder 18 is mounted on the jaw 11. Holder 10 18 also includes a recessed clamping portion 20 for receiving the enlarged head 21 of a safety razor blade 22. The ends of the clamping portion 20, as seen in Figure 4, are open to permit the razor blade 22 to be detached therefrom by 15 being moved longitudinally thereof. Clamping portion 20 is restricted at its bottom, at 23, to prevent lateral movement of the blade 22, in one direction relatively to the holder 18 while the portion 16, on which the holder 18 is mounted, 20 prevents lateral movement of the blade 22 in the opposite direction. The holder 18 is further provided with a reinforcing flange 24 which extends from one side of the clamping portion 20 and which engages against one side of the blade 22. 25 Flange 24 terminates above the cutting edge 25 of the blade 22.

A cutter frame 26 is provided with a recessed head 27 which is slidably mounted on the portion 16 of the jaw 12. A blade element 28 extends 30 therefrom, inwardly of the portion 16. One side of the blade element 28 slidably engages against the exposed side of the razor blade 22. The free edge of the blade element 28 is beveled on its 35 opposite side to provide a cutting edge 29 which is tapered toward the outer end of the frame 26 which end and the corresponding portion of the head 27 are beveled at 30. The opposite end of the blade element 28 is elongated and flared outwardly, away from the blade 22, to form a guide 40 31 for a purpose which will hereinafter be described.

From the foregoing it will be seen, that the 45 holder 18 and the cutter frame 26 are slidably mounted on the portions 16 of the jaws 11 and 12, respectively, so that either the holder or frame is readily detachable by being moved outwardly relatively to the jaws. When the shear frame 10 is in a closed position, as illustrated in Figures 1 and 3, the cutting edges of the blade 22 50 and cutting element 28 are in overlapping relationship. By opening the handles 13 and 14 portions 16 of the jaws 11 and 12 will be moved away from one another to move the cutting edges of the razor blade 22 and cutting element 28 out 55

of engagement with each other. As the jaws are again moved toward a closed position the inner end of the cutting edge 25 will engage the guide 31 by means of which it will be guided into proper engagement with the element 28. Due to the 5 taper of the cutting edge 29 and to the swinging movement of the portions 16, the cutting edges 25 and 29 will execute a shearing cut similar to the conventional scissors. The reinforcing flange 24 is provided to prevent the cutting 10 edge of the razor blade 22, which is relatively flexible, from springing outwardly when contacting an article disposed between the cutting edges 25 and 29 and to thereby maintain the cutting 15 edges in engagement during the cutting stroke so that the proper shearing action will be obtained. As heretofore mentioned, the razor blade 22 may be removed longitudinally from the holder 18 and replaced by a new blade when dull and the cutting 20 frame 26 may be removed from its supporting portion 16 and replaced or sharpened thus eliminating the necessity of sharpening the blades as is required in conventional scissors or shears.

The shears 10 may also be used as a knife by 25 detaching the holder 18, reversing it and reapplying it so that the razor blade 22 extends away from the jaws 11 and 12, as seen in Figure 2.

Various modifications and changes are contemplated and may obviously be resorted to as 30 only a preferred embodiment of the invention has been illustrated and described.

I claim as my invention:

1. A scissors comprising a shear frame including a pair of pivotally connected handle members, 35 portions formed integral with and disposed at an angle to said handle members, said portions projecting in opposite directions to aline in one position, polygonal shaped shanks formed integral with said portions and projecting therefrom substantially at right angles thereto, said shanks being parallel when said portions are alined; a frame including a portion shaped to closely engage one of said shanks, said frame portion terminating in spaced jaws for engaging the head of a safety razor blade and being provided with inturned portions for engaging beneath said head, one of said portions being elongated to engage against one side of the blade to provide reinforcing means therefor; a second 40 frame having a portion shaped to closely engage the other shank, a blade element formed integral with said second frame and projecting from the shank engaging portion, the exposed side of said razor blade being positioned to slidably engage one side of said blade element, and said blade element having its free edge tapered toward its outer end and beveled on its opposite side to provide a cutting edge for co-acting with the razor blade.

60 2. A device as in claim 1, said blade element having an upwardly projecting flange in its inner

end flared away from the razor blade and forming a guide for the cutting edge thereof for directing its cutting edge into proper cutting engagement with the cutting edge of the blade element when the razor blade and blade element are moved 5 toward a closed position.

3. A scissors comprising a shear frame comprising a pair of pivotally mounted jaws having actuating handles, said jaws each forming a right angle and having corresponding free ends disposed in spaced apart parallel relationship, when in a closed position, said free ends being polygonal shaped in cross section, a blade holder having a recessed head portion for slidably and demountably engaging one of said free ends, clamping elements carried by said head for engaging the head of a safety razor blade, one of said clamping elements being elongated and in the form of a flange for engaging against one side of the razor blade, a second frame having a head portion 10 slidably and detachably mounted on the free end of the other jaw, a cutting element projecting inwardly of said jaws from said second head portion for engaging the opposite side of the razor blade, and said cutting element having a 15 beveled cutting edge on its exposed side, said cutting edge tapering toward the outer end of the frame to produce a shearing cut with the cutting edge of the razor blade when the jaws are actuated.

4. In a scissors, a shear frame having jaws disposed in spaced apart substantially parallel relationship in one position, a holder having a recessed head portion for slidably and demountably engaging one of said jaws, said holder being provided with means for detachably engaging a head of a razor blade, a frame having a recessed head portion for slidably and demountably engaging the other jaw, said head portions and jaws being polygonal shaped in cross section, a 35 blade element projecting from said frame and having one of its sides in sliding engagement with a side of the razor blade, the free edge of said blade element being beveled on its opposite side to form a cutting edge for co-acting with the sharpened edge of the razor blade, and said cutting edge being tapered toward the outer end of the frame.

5. A tool as in claim 4, comprising a flange formed integral with and depending from said holder for engaging the opposite side of the razor blade and forming reinforcing means therefor.

6. A tool as in claim 4, the inner end of said cutting element being enlarged and curved away from the razor blade to form a guide for the cutting edge of the razor blade when the cutting edges are moving toward one another.

7. A tool as in claim 4, said blade holder being reversible on its supporting jaw for positioning the razor blade for use as a knife.

BYRON L. ATCHISON.
